UNITED STATES PATENT OFFICE.

GILBERT L. CROWELL, JR., OF ARLINGTON, NEW JERSEY, ASSIGNOR TO
DOMINICK & HAFF, OF NEW YORK, N. Y.

DESIGN FOR A SPOON.

SPECIFICATION forming part of Design No. 20,773, dated May 26, 1891.

Application filed April 28, 1891. Serial No. 390,843. Term of patent 14 years.

To all whom it may concern:

Be it known that I, GILBERT L. CROWELL, Jr., a citizen of the United States, and a resident of Arlington, in the county of Hudson 5 and State of New Jersey, have invented and produced a new, original, and useful Design for Spoon-Bowls, of which the following is a description, reference being made to the accompanying drawing, which illustrates the 10 design as embodied in an orange-spoon.

The general outline of the main lower or lip portion of the bowl is conical, the sides *a* being, however, moderately convex, and the point or tip being slightly rounded. At the 15 top thereof the outlines of the bowl turn inwardly toward and join the shank *b* of the

handle by recurring lines, forming in effect the shoulders *c* and *d*. Within and under these shoulders the bowl is shaped to have separate concavities *e*, which merge into or 20 join the general bowl concavity by unbroken curvatures. This bowl may have any suitable handle, the handle shown in the drawing forming no part of the design.

What is claimed as new is—

The design for spoon-bowls, substantially 25 as herein shown and described.

GILBERT L. CROWELL, JR.
